UNITED STATES PATENT OFFICE.

HERBERT T. LINDFORS AND WILLIAM B. LOLLIS, OF COLUMBIA, SOUTH CAROLINA.

LOCOMOTIVE DRIVING BOX.

Application filed April 16, 1924. Serial No. 706,970.

To all whom it may concern:

Be it known that HERBERT T. LINDFORS and WILLIAM B. LOLLIS, citizens of the United States, residing at Columbia, in the county of Richland and State of South Carolina, have invented new and useful Improvements in Locomotive Driving Boxes, of which the following is a specification.

10 This invention relates to improvements in driving boxes for vehicle wheels, and particularly to adjustable wedging means for taking up excessive lateral play between the driving box and the hub of a locomotive

15 wheel.

When the excess lateral motion between a locomotive wheel and its driving box exceeds a predetermined amount, Government regulations require that it be immediately 20 reduced to within certain limits. Heretofore it has been necessary in order to correct for this excess lateral play, to remove the wheel and axle from the locomotive, which entails considerable expense and 25 delay.

A primary object of the present invention consists in the provision of means positioned between the ends of the driving box and the supporting frame, whereby any excess lateral movement can be quickly corrected without the necessity of dismantling any of the parts, by simply adjusting the wedges, which will effectively maintain the driving box substantially square to the hub 30 of the wheel at all times.

A further object of the invention relates to the provision of an adjustable wedge positioned between one side of the supporting frame and the driving box, which may 40 be readily adjusted when the parts become loose, so as to maintain the frame and the axle in proper relation.

Referring to the drawings, wherein is set forth a preferred embodiment of the invention:

Figure 1 is a sectional view taken substantially along the line 1—1 of Figure 3,

Figure 2 is a vertical sectional view taken substantially along the line 2—2 of Figure 1,

50 Figure 3 is a sectional view taken substantially along the line 3—3 of Figure 1,

Figure 4 is a view taken substantially along the line 4—4 of Figure 6, and shows a modified form of the invention,

Figure 5 is a sectional view taken substantially along the line 5—5 of Figure 4, and

Figure 6 is a sectional view taken substantially along the line 6—6 of Figure 4.

Referring to the drawings, wherein like numerals indicate like parts in the several views, 10 denotes the frame of a locomotive, or the like, having an opening 11 therein, in which is supported the driving box 12. The axle 13 journalled in the driving box 12 has secured thereto the locomotive wheel 14 in any suitable manner.

The driving box 12 is provided with a semi-circular bushing 15 which engages the axle 13, and is also formed with the depending arms or pedestals 16 and 17, having the lugs 18 and 19, respectively arranged to register with the complementary lugs 20 and 21 on the saddle plate 22, and detachably connected thereto, by the bolts 23 and 24, as shown in Figure 1.

In order that excessive lateral motion between the driving box 12 and the face of the hub 25 of the locomotive wheel may be readily taken up, without the necessity of dismantling any of the parts, the driving box 12 is preferably provided with the outward projecting, radial, end flanges 26 and 27, as shown in Figure 3. Interposed between the pedestals 16' and 17' of the frame 10 and the adjacent sides of the driving box, there are arranged a pair of slippers 28 and 29, having end flanges 30 and 31, which extend parallel with and engage the flanges 26 and 27 of the driving box.

The opposed inner walls of each of the flanges 30 and 31 are preferably recessed and tapered downwardly, as at 32 and 33, so as to receive and frictionally engage the complementary faces of wedges 34, 35, 36 and 37, positioned between the frame 10 and the end flanges 26 and 27, for co-acting with the slippers in maintaining the driving box in proper position relative to the wheel 14. By reason of the recesses 32 and 33 formed in the slippers, the wedges will be prevented from moving laterally when the parts are set up.

The wedges are each provided with threaded shanks 37 which extend through suitable openings formed in braces 38, preferably secured to the lower portion of the frame 12. The wedges are maintained in

fixed adjusted position relative to the slippers by means of the retaining nuts 39 and 40 threaded to each of the shanks 37.

In order to reduce to a minimum the amount of lost motion between the driving box and the frame 10, a wedge 41 is preferably positioned between the pedestal 17' of the box and the adjacent surface of the slipper, as shown in Figure 3. The wedge 41 has connected to its lower end a threaded bolt 42 which extends through the frame 10 and is maintained in position thereon by the retaining nut 43, as shown in Figure 2.

To overcome excessive lateral play between the driving box 12 and the locomotive wheel 14, it will be merely necessary to loosen the inside wedges 34 and 37 and tighten the outside wedges 35 and 36 by suitably adjusting the nuts 39 and 40 on the shanks 37'. As these wedges are independently adjustable, they may be separately regulated to secure any desired adjustment. Furthermore, should it be required to take up lost motion between the side of the driving box and the frame 10, this can be done by tightening or loosening the wedge 41, as may be required.

By reason of the present construction, it will be apparent that any lost motion or excess lateral play between the frame 10, the driving box 12, and the wheel 14 can be readily corrected by making the necessary adjustment to the several wedges, as before set forth, without the necessity of dismantling the parts.

In the modified form of the invention illustrated in Figures 4, 5 and 6, the rear wedges are shown connected at the top of the frame, while the forward wedges are attached to the bottom thereof in contradistinction to having all the wedges secured to the bottom of the frame, as shown in the form previously set forth. Otherwise the construction and operation of the parts are identically the same as those previously described.

Referring particularly to the modified form of the invention, the driving box 44 is movably maintained in the supporting frame 45 by means of the end flanges 46 and 47, between which and the adjacent ends of the frame are interposed the slippers 48 and 49. These slippers are provided with the flanges 50 and 51 formed on their inner surfaces with downwardly tapered recesses 52 and 53 which receive the complementary tapered surfaces of the wedges 54, 55, 56 and 57, respectively.

The threaded shanks 58 of the inside wedges 54 and 55 are preferably connected to the top of the supporting frame 45 by the bracket 59, to which the shanks 58 are adjustably secured by the nuts 60 and 61, as shown in Figure 5. Similarly, the outside wedges 56 and 57 have their shanks 58 con-

nected to the braces 62 on the underside of the frame 45 by means of the nuts 63 and 64. Obviously, this particular arrangement could be reversed without in any way departing from the scope of the invention.

A wedge 65 preferably interposed between the slipper 49 and the adjacent wall of the frame 45 is provided to compensate for any excessive lost motion between the driving box and the frame member. A threaded bolt 66 connected to the lower end of the wedge 65 projects through a suitable opening formed in the frame 45 for permitting the wedge to be adjusted relative to the supporting frame, and is maintained in predetermined position by the nut 67.

The axle 68 having the wheel 69 connected thereto, is mounted within the driving box 44 and is detachably connected thereto by means of the saddle plate 70 which is attached to the frame by the retaining bolts 71 and nuts 72.

When excessive lateral motion occurs between the driving box 44 and the locomotive wheel 69, it can be readily corrected by selectively adjusting the several wedges in the manner as may be desired. Furthermore, should it be necessary to take up lost motion between the driving box and the frame, the wedge 65 can readily be tightened.

It is to be understood that the forms of the invention herewith shown and described are merely illustrative and in no sense restrictive, and that such changes as fall within the purview of one skilled in the art may be made without departing from the spirit of the invention and the scope of the appended claims.

We claim:

1. In a vehicle of the class described, the combination with a supporting frame having an opening therein, of a driving box mounted within said opening, and means between the ends of said driving box and said frame for adjusting the driving box relative to the frame.

2. In a vehicle of the class described, the combination with a frame having an opening therein, of a driving box mounted within said opening, and adjustable means between the ends of said driving box and said frame for adjusting the driving box relative to the frame.

3. In a vehicle of the class described, the combination with a vehicle frame having an opening therein, of a driving box slidably mounted within said opening, a slipper adjacent each end of the driving box, and a wedge between each of said slippers and the frame.

4. In a vehicle of the class described, the combination with a supporting frame having an opening therein, of a driving box slidably mounted within said opening, a

slipper adjacent each end of the driving box, a wedge between each of said slippers and the frame, and means for adjusting the wedges relative to the slippers.

5. In a locomotive, the combination with a supporting frame having an opening therein, of a driving box slidably mounted within said opening, a slipper adjacent each end of the driving box, a wedge between each of

10 said slippers and the frame, and means for independently adjusting the wedges relative to the slippers.

6. In a locomotive, the combination with a supporting frame having an opening therein, a driving box slidably mounted within said opening, a slipper adjacent each end of the driving box, each of said slippers having a recessed inner surface, and a wedge between each of said slippers and the frame

20 and adapted to fit in said recess.

7. In a locomotive, the combination with a supporting frame having an opening therein, a driving box slidably mounted within said opening, a slipper adjacent each end of the driving box, each of said slippers having a recessed inner surface, a wedge between each of said slippers and the frame adapted to fit in said recess, and means for independently adjusting the wedges relative to

30 the slippers.

8. In a locomotive, the combination with a supporting frame having an opening therein, a driving box slidably mounted within said opening, a slipper adjacent each end of the driving box, each of said slippers having a recessed inner surface, a wedge between each of said slippers and the frame adapted to fit in said recess, and means projecting from each of the wedges and connected to

40 the frame for adjusting the wedge relative to its adjacent slipper.

9. In a locomotive, the combination with a supporting frame having an opening therein, of a driving box slidably mounted within said opening, slippers adjacent each end of the driving box, a wedge between each of said slippers and the frame, and an adjustable shoe between one side of the frame and the driving box.

50 10. In a locomotive, the combination with a supporting frame having an opening therein, of a driving box slidably mounted within

said opening, slippers adjacent each end of the driving box, each of said slippers having a tapered recessed inner surface, a correspondingly tapered wedge between each of said slippers and the frame adapted to fit in the recess of its adjacent slipper, and a tapered shoe between one side of the frame and the driving box.

11. In a locomotive, the combination with a supporting frame having an opening therein, of a driving box mounted in said opening, an axle journalled in said driving box, a wheel connected to said axle, said driving box having opposed end flanges, flanged slippers between said driving box and frame on each side of the axle, the opposed inner surfaces of said flange slippers having tapered recesses therein, and a wedge between each of said slippers and the frame.

12. In a locomotive, the combination with a supporting frame having an opening therein, of a driving box mounted in said opening, an axle journalled in said driving box, a wheel connected to said axle, said driving box having opposed end flanges, flanged slippers between said driving box and frame on each side of the axle, the opposed inner surfaces of said flange slippers having tapered recesses therein, a wedge between each of said slippers and the frame, and means projecting from each of the wedges and connected to the frame for adjusting the wedges relative to their adjacent slippers.

13. In a locomotive, the combination with a supporting frame having an opening therein, of a driving box mounted in said opening, an axle journalled in said driving box, a wheel connected to said axle, said driving box having opposed end flanges, flanged slippers between said driving box and frame on each side of the axle, the opposed inner surfaces of said flange slippers having tapered recesses therein, a wedge between each of said slippers and the frame, and a tapered shoe between one side of the frame and the driving box.

In testimony whereof we have hereunto set our hands.

HERBERT T. LINDFORS.
WILLIAM B. LOLLISS.
